WASHING MACHINE

Royal R. Miller, Chicago, Ill., assignor of one-half to Remi J. Gits, Riverside, Ill.

Application July 20, 1936, Serial No. 91,482

14 Claims. (Cl. 68—28)

This invention relates to washing machines, and particularly to washing machine agitators and agitator and bowl arrangements which are operable in accordance with the general scheme 5 disclosed in my co-pending applications, Serial No. 9,803 filed March 7, 1935, and Serial No. 56,192, filed December 26, 1935.

The main objects of this invention are to provide an improved washing machine agitator; to 10 provide an improved agitator construction; to provide an agitator capable of more efficiently agitating the contents of a washing machine; to provide an agitator that will produce an improved suspended and cushioned tumbling action 15 of the material being washed; to provide an improved washing machine bowl and agitator arrangement whereby greater operating efficiency is obtained; to provide such an arrangement wherein the water currents are more positively 20 and efficiently directed to obtain most effective agitation; and to provide an improved agitator in which mechanical resistance to the flow of water currents around the agitator is reduced to a minimum.

25 A specific embodiment of this invention is shown in the accompanying drawings, in which

Fig. 1 is a sectional elevation of a washing machine embodying the improved agitator construction and agitator and bowl arrangement.

30 Fig. 2 is a bottom plan view of the agitator partially broken away and showing an arrangement of perforations and reinforcement for the agitator disc.

Fig. 3 is a sectional elevation of the improved 35 agitator showing its construction more in detail.

Fig. 4 is a fragmentary sectional elevation of a modified form of the improved agitator, and

Fig. 5 is a partially sectioned fragmentary view, 40 in elevation, of the agitator carrying head showing an improved arrangement for securing the same onto the main drive shaft.

In the form shown in the drawings the improved agitator comprises essentially a flat annular disc having an upwardly tapered central portion 45 which forms a hub arranged to be journaled on a shaft eccentrically carried by a main drive shaft and inclined upwardly and inwardly so that its axis will intersect the axis of the main drive shaft. The agitator is disposed within a bowl-shaped tub, the lower side wall portion of which is spherically shaped and located so that the center of curvature of the spherically shaped portion will substantially coincide with the point 50 of intersection of the agitator shaft axis and the axis of the main drive shaft which projects ver-

tically upward from the bowl bottom. Thus the agitator extends transversely of the tub and is supported in a tilted position with the plane of the disc always at an angle relative to the tub bottom or the horizontal.

As shown in Fig. 1 the washing machine comprises an outer shell or casing 1, mounted upon a base 2, which in turn is supported on wheels 3 which, by an arrangement not shown, may be retracted to allow the base 2 to rest directly upon the floor. In the lower portion of the casing 1 is a transversely extending base plate 4 dividing the casing into upper and lower sections. A water bowl or container 5 is housed in the upper section of the casing 1, with its bottom disposed close to the base plate 4; and a drive mechanism 6 is disposed in the lower section of the casing 1 and has a main drive shaft 7 extending upwardly through the base plate 4 and the bottom of the bowl 5 through a suitable housing and seal arrangement 8.

The casing 1 and the bowl 5 are together arranged to provide a relatively large top opening through which access is had to the interior of the bowl 5, and a removable cover 9 is provided 25 as a closure for the top opening.

As shown in Fig. 1 the main drive shaft 7 extends a relatively short distance into the interior of the bowl 5, extending upwardly from the bottom thereof in a central position. Within the bowl 5 and on the end of the main drive shaft 7 closely adjacent the bowl bottom is a suitable driving head 10 having an upwardly and inwardly tapered hexagonal bore formed to receive and fit a similarly tapered hexagonal end of the shaft 7. The head 10 is arranged to carry an agitator shaft 11, made of steel or any other suitable hard wearing material, which in the form shown is cast into an eccentric angularly disposed portion 12 of the head 10 and so positioned as to extend upwardly and inwardly with its axis intersecting the axis of the main drive shaft 7 at the point C.

The water bowl or tub 5 is an annular body provided with a relatively flat horizontal bottom 13 from the margins of which the side wall extends outwardly and upwardly in an arcuate curve having its center at the point C, the side wall continuing vertically upward from the level of the point C, thus forming a body, the lower portion of which is in the form of a truncated 50 hemisphere and the upper portion of which is cylindrical.

The improved agitator 14 comprises a flat annular disc portion 15 and an upwardly tapered central portion 16 which is normal to the plane 55

of the disc portion 15 and arranged to provide a hub for mounting the agitator onto the agitator shaft 11. The agitator 14 is preferably made as a single casting and as shown the central portion 16 terminates a short distance above the end of a bore 17 in which shaft 11 is journaled. As shown the upper end of the central portion of the agitator is provided with an externally threaded boss 18 on which a tapered tip or post 19 is secured by means of threaded engagement with the boss 18, the post 19 extending upwardly to a point adjacent the top opening of the bowl 5.

The post 19 is made with an outside diameter at its lower end substantially equivalent to the outside diameter of the central agitator portion 16 at its top, so that the outer surface of the post 19 will be flush with the outer surface of the central portion 16 at the point where the post and the agitator are joined.

The agitator herein shown is proportioned so that the main body of the upwardly extending central portion 16 of the agitator and the post 19 taper upwardly in a gentle curve so as to more effectively direct the downward flow of the water currents produced by the agitator when the agitator is in operation; and also to obviate any tangling or twisting on the post 19 and central portion 16, of the material being washed. For example, in the device which is illustrated herein the agitator disc 15 is made with a diameter of approximately eighteen and one-half inches and the tip of the post 19 is approximately fourteen and one-half inches above the upper face of the disc 15 terminating in a rounded portion about one-half inch wide. The radius of curvature of the upward taper of the central portion 16 and post 19 is approximately thirty-six inches and this curve is blended into the plane surface of the disc 15 through a tangential curve having a radius of approximately two and three-fourths inches. It has been found that such proportions have a material effect upon the efficiency of the device as a washer, particularly in that a greater amount of tumbling of the clothes and a more rapid travel from side to center to side is had than is possible with former arrangements or constructions.

In the form shown in the drawings the central portion 16 of the agitator, in which the hub is formed, flares downwardly outward away from the hub 20, leaving the hub as a cylindrical portion, centrally disposed, extending downwardly from the upper part of the central portion 16. The annular disc portion 15 is formed at right angles or normal to the axis of the hub 20 and is provided with a flat smooth even upper surface, uninterrupted by any manner of ribs, fins, or other projections.

As shown in Figs. 1, 2 and 3, a reinforcement is provided on the under side of the agitator disc 15 and comprises a flat bead 21 formed on the outer margin of the disc and a plurality of radially extending thickened portions 22 which join into the flat marginal bead 21. The reinforcing portions 21 and 22 are made quite wide as shown and curve slowly from their crests into the lower surface of the disc so as to offer the least amount of resistance possible to the flow of the water currents under the agitator and over the outer margin. Thus the bead 21 comprises a marginal bulge, on the under side of the disc 15, which tails off gradually into the disc surface and the radial reinforcements 22 are beaver-tailed in section, tapering off gradually from each side of their respective radial center lines.

The flat disc portion 15, as shown, is provided with perforations which are preferably closely spaced and extend over the entire flat area of the agitator in a pattern such as that illustrated in Fig. 2. These perforations serve several purposes and particularly that of causing upward spurts or jets of water, on the descending side of the agitator, which cause a more rapid movement and turn over of the material being washed as well as the function of directing the material toward the upper side portion of the tub and counteracting the tendency of the material from merely following the disc in its up and down movement.

As shown, the radial reinforcements 22 of the agitator disc extend inwardly and into the central portion 16 where they join into the hub portion 20 somewhat above the end thereof.

The lower end of the hub 20 is inwardly beveled as at 23 and an outwardly flared funnel shaped collar 24 is disposed over the lower end of the hub 20 so as to facilitate entrance of the agitator shaft 11 into the bore 17.

The collar 24 is a press fit onto the hub 20 and the outwardly flared portion extends to the side wall of the central portion 16 of the agitator, the portion of the collar embracing the hub 20 being of such length as to engage the reinforcements 22 at the point where they join the hub 20, thus maintaining the flared portion of the collar in a position substantially flush with the beveled portion 23 of the hub 20 so that the end of the shaft 11 will readily enter the bore 17 when the agitator is being set upon the shaft.

The agitator as shown merely rests upon the shaft 11 and is not secured thereto, and in order to provide adjustment of the position of the agitator on the shaft 11 a set screw 25 (see Fig. 1), is mounted in a threaded bore 26 extending axially through the boss 18 and into the bore 17. The set screw 25 is arranged to engage the end of the shaft 11 and thus provide a limit stop determining the amount that the shaft 11 will extend into the bore 17. A lock nut 27 is provided on the upper end of the set screw 25 and engages the end of the boss 18 to prevent inadvertent change of adjustment of the set screw 25.

A modified arrangement of the improved agitator is illustrated in Fig. 4 and the modification comprises mainly the upturned or curved annular margin 28 of the disc portion 15. In this arrangement the upturned margin 28 is curved on a radius equivalent to substantially four times the thickness of the disc portion of the agitator or, according to the proportions shown, about one-half inch, and the inner corner of the upper edge 55 of the margin 28 is rounded as at 29.

The upturned margin 28 of the modified form of agitator obviates the necessity of employing the reinforcements 21 and 22 shown on the agitator construction illustrated in Fig. 3, the upwardly extending margin serving their function.

As shown in Fig. 5 the head 10 which carries the agitator shaft 11 is provided with a tapered bore shaped to fit the tapered hexagonal end portion 30 of the shaft 7, and is locked thereto by means of a screw 31 which extends through the end of the head portion 10 and into the tapered portion 30 of the shaft 7, the faces of the tapered portion 30 serving to key the head 10 onto the shaft 7.

As shown in Fig. 1 the agitator 14 is disposed on the shaft 11 so as to fit closely to the bottom 13 of the bowl 5, the exact position being determined by the angle of the agitator shaft 11 and the maintenance of a reasonable clearance be- 75

5 tween the lowermost portion of the agitator disc 15 and the bowl bottom 13. Thus the agitator disc 15 is set low in the tub 5 and extends transversely thereof from side to side at an angle relative to the plane of the bowl bottom. Also the bowl or tub 5 is so proportioned relative to the diameter of the agitator disc 15 that there will be a clearance of approximately one-sixteenth of an inch between the outermost periphery of the disc 15 and the side wall of the tub or bowl.

10 This clearance may vary somewhat due to manufacturing tolerances, but it is intended that the margin of the disc 15 should always closely follow the wall of the bowl or tub 5. The location of the tub wall relative to the agitator disc 15 is shown by the dotted line in Figs. 3 and 4.

15 The improved agitator is preferably made with its upper or clothes-contacting surfaces polished smooth so as to minimize friction, and with its lower surface in the area of the disc portion 15 buffed or brushed so as to be smooth. Thus it will be apparent that whatever agitation of the water or material contained in the bowl 5 is had will be mainly derived from water currents produced 20 by the movement of the agitator, rather than by any fins or other structural element which might directly engage the clothes or have a lateral paddling action on the water.

25 In operation the agitator 14 is freely rotatable upon the shaft 11 and the shaft 11 is gyrated about the axis of the main drive shaft 7, thus gyrating the agitator 14 about the axis of the shaft 7 so that the raised and lowered portions of the disc 15 tend to travel in horizontal paths 30 about the wall of the tub 5. However, due to the fact that the agitator is freely rotatable on the shaft 11 there is a tendency for the shaft 11 to turn in the bore 17, causing the agitator 14 to wobble from side to side during the gyrating movement of the shaft 11. This wobble movement is due to the fact that the inertia of the agitator 14 and the resistance caused by the 35 contents of the tub prevents the agitator being rotated at the same speed as the head 10. The result is that each portion of the agitator disc will be alternately raised and lowered as though the agitator were suspended at the point C and oscillated from side to side pendulously while at the same time being rotated on the point of suspension.

40 During such wobble movement the tub contents are strongly agitated due to revolving water currents that are created by the agitator and the material being washed is tumbled about both a horizontal and a vertical axis. The water currents tend to follow the paths indicated by the arrows in Fig. 1 and because of their revolving movement substantially suspend the material in the water above the agitator so that 45 contact with the agitator is reduced to a minimum.

45 Because of the polished smooth even upper surface of the agitator the speed and strength of the water currents is greatly increased over that of other devices and arrangements. Also friction between the material being washed and the agitator is reduced to a minimum as far as any wearing or beating effect is concerned. There 50 being no ribs or fins or other projections on the agitator surface, the danger of the material being torn, beaten, whipped or otherwise being roughly treated, is obviated. Instead a steady suspended cushioned tumbling action is had. Also a more 55 rapid turn over of the material is obtained than

with other devices and thus a more rapid washing or cleansing action.

5 The elimination of vertical fins or ribs, which the present invention accomplishes, also permits the handling of a greater material load with maximum efficiency than can be taken with other washing machines having the same volumetric capacity.

10 It will be observed that though there is a small space between the margin of the agitator disc 15 and the spherical side wall of the tub, the material being washed will not enter or become caught between the agitator and the tub because of the fact that there is a substantially constant upward water current passing over the edge of 15 the agitator disc, thus forcing the material away from the said space.

15 The main advantages of the present invention are derived from the improved agitator construction and the resultant agitator and bowl arrangement or combination, whereby a greatly improved and more rapid washing action is obtained. The minimizing of friction by providing a smooth even upper surface for the agitator is unprecedented, as other constructions are either 20 provided with ribs or with vertical or spiral fins which act laterally upon both the water and the material being washed. Also the location of the disc agitator below the material being washed further obviates the possibility of any beating 25 action on the material. Another advantage is in the spherical bowl and agitator arrangement whereby a maximum of free open space is provided in the bowl for holding the washing load 30 and for the removal of the same.

35 Although but two specific embodiments of this invention are herein shown and described it will be understood that numerous details of the construction shown may be altered or omitted without departing from the spirit of this invention 40 as defined by the following claims.

I claim:

1. In a washing machine, a tub having a spherical inside wall surface, an agitator disposed adjacent the bottom of said tub and comprising a flat disc portion extending transversely of said tub, said agitator having a multiplicity of small closely spaced perforations in said flat disc portion and occupying a major portion of the area thereof and having a polished smooth upper surface, a rotatable driving means extending upwardly from the bottom of said tub, and a connection between said driving means and said agitator arranged to support said agitator in a tilted position relative to the bottom of said tub and to impart a rotary pendulous motion to said agitator relative to the spherical center of said tub.

2. In a washing machine, a tub having a spherical inside wall surface, an agitator disposed adjacent the bottom of said tub and comprising an upwardly tapered central portion extending substantially to the top of said tub and a flat annular disc portion extending transversely of said tub and disposed in one plane normal to said central portion, a centrally disposed rotatable driving means extending upwardly from the bottom of said tub, and a connection between said driving means and said agitator arranged to support said agitator in a tilted position relative to the bottom of said tub and to impart movement to said agitator such that the axis of said central portion describes a cone having its apex above the agitator and at the spherical center of the tub.

3. In a washing machine, a tub, an agitator disposed adjacent the bottom of said tub and comprising an upwardly tapered central portion extending substantially to the top of said tube and a flat annular disc portion normal to said central portion and extending transversely of said tub, said agitator having a smooth even upper surface devoid of projections other than said central portion, a rotatable driving means extending vertically upwardly from the bottom of said tub, and a connection between said driving means and said agitator arranged to support said agitator in a tilted position relative to the bottom of said tub.
4. In a washing machine, a tub, an agitator disposed adjacent the bottom of said tub and comprising an upwardly tapered central portion extending substantially to the top of said tub and a flat annular disc portion extending transversely of said tub and normal to the axis of said central portion, said agitator having a smooth even upper surface devoid of projections other than said central portion and closely spaced perforations in said flat disc portion, a rotatable driving means extending vertically upwardly from the bottom of said tub, and a connection between said driving means and said agitator arranged to support said agitator with the axis of said central portion tilted relative to the axis of said driving means.
5. A washing machine comprising a tub having a spherical inside wall surface adjacent its bottom, an agitator disposed adjacent the bottom of said tub below the spherical center of said wall surface and having a flat annular disc portion extending transversely of said tub, the margins of said disc portion being in close proximity to said spherical wall surface, and a centrally disposed rotatable driving means extending vertically upward from the bottom of said tub and arranged to support said agitator in a tilted position with the central transverse axis of said agitator intersecting the axis of said driving means at the spherical center of said wall surface.
6. A washing machine comprising a tub having a spherical inside wall surface adjacent its bottom, an agitator disposed adjacent the bottom of said tub below the spherical center of said wall surface and having a flat annular disc portion extending transversely of said tub and an upwardly tapered central portion normal to said disc portion and extending substantially to the top of said tub, said agitator having a smooth even upper surface devoid of projections other than said central portion and the margins of said disc portion being in close proximity to said spherical wall surface, and a rotatable driving means extending vertically upward from the bottom of said tub and arranged to support said agitator in a tilted position with the axis of said central portion intersecting the axis of said driving means at the spherical center of said wall surface.
7. A washing machine agitator comprising a flat transversely extending disc portion, an upwardly tapered central portion, and a hub housed in said central portion, said disc portion and said central portion having a smooth even upper surface devoid of projections therefrom.
8. A washing machine agitator comprising an upwardly tapered central portion the base of which flares outwardly into a flat disc portion extending transversely and normal to the axis of said central portion, and a hub in said central portion, said central portion and said disc portion having a smooth even upper surface devoid of projections therefrom.
9. A washing machine agitator comprising an upwardly tapered central portion the base of which flares outwardly into a flat disc portion extending transversely and normal to the axis of said central portion, and a hub in said central portion, said central portion being tapered throughout its length and together with said disc portion having a polished smooth upper surface uninterrupted by lateral and vertical projections.
10. A washing machine agitator comprising a hollow upwardly tapered central portion the base of which flares outwardly into a portion extending transversely of the axis of said central portion, a hub housed wholly within said hollow central portion and integral therewith at its upper end, said hub being spaced from the side wall of said central portion at its lower end and having an axial bore, and a collar secured on the lower end of said hub and having a conical flange the inner margin of which is flush with the end of said hub, said flange extending downwardly and outwardly to the side wall of said central portion to close off the space between the lower end of said hub and said side wall.
11. A washing machine agitator comprising a hollow upwardly tapered central portion the base of which flares outwardly into a flat disc portion extending transversely and normal to the axis of said central portion, a hub housed wholly within said hollow central portion and integral therewith at its upper end, said hub being spaced from the side wall of said central portion at its lower end and having an axial bore, and a collar secured on the lower end of said hub and having a conical flange the inner margin of which is flush with the end of said hub, said flange extending downwardly and outwardly to the side wall of said central portion to close off the space between the lower end of said hub and said side wall.
12. A washing machine agitator comprising a flat annular transversely extending disc portion, a relatively long upwardly tapered central portion normal to the plane of said disc portion, an upwardly turned flange at the marginal edge of said disc portion, and a hub housed within said central portion, said disc portion and said central portion having a smooth even upper surface devoid of projections therefrom.
13. In a washing machine, a tub arranged for holding a washing liquid and having a spherical inside wall surface adjacent the bottom thereof, a rotatable driving means extending vertically upward from the bottom of said tub, an agitator comprising a flat annular disk disposed in said tub transversely adjacent the bottom thereof and having an upwardly tapering central portion normal to the plane of said disk and extending substantially to the top of said tub, and a connection between said driving means and said agitator arranged to support the agitator so that the disc portion thereof is disposed in a plane which is non-perpendicular to the axis of rotation of said driving means and to pendulously rotate said agitator below the spherical center of said inside wall surface.
14. In a washing machine, a tub arranged for holding a washing liquid and having a spherical inside wall surface adjacent the bottom thereof, a rotatable driving means extending vertically upward from the bottom of said tub, an agitator comprising a flat annular disk disposed in said central portion having a smooth even upper surface devoid of projections therefrom.

5 tub transversely adjacent the bottom thereof and having an upwardly tapering central portion normal to the plane of said disk and extending substantially to the top of said tub, said disk being devoid of projections other than said central portion, and a connection between said driving means and said agitator for supporting the

agitator so that said disk is disposed in a plane which is non-perpendicular to the axis of rotation of said driving means and for pendulously oscillating said agitator below the spherical center of said inside wall surface.

5

ROYAL R. MILLER.
